UNITED STATES PATENT OFFICE.

SAMUEL K. LIGHTER, OF HAMILTON, OHIO.

IMPROVEMENT IN HARVESTERS.

Specification forming part of Letters Patent No. 40,488, dated November 3, 1863.

To all whom it may concern:

Be it known that I, SAMUEL K. LIGHTER, of Hamilton, Butler county, Ohio, have invented a new and useful Improvement in Harvesters; and I do hereby declare the following to be a full, clear, and exact description thereof, reference being had to the accompanying drawings, making part of this specification.

My improvement relates to a provision for combining the advantages both of a stiff and of a limber tongue without the use of trucks or truck-wheels.

A represents a portion of the main beam. B is a peculiarly formed and attached bracket, fastened to the side of the beam A by means of a center bolt or pivot, C, and two tightening-bolts, D D', which traverse slots E E' in the bracket, said slots forming arcs of a circle concentric with the pivot C. To this bracket B the tongue F is secured through the medium of a wedge-formed block, H, which I term the "socket-block." The top of the block H sloping upward toward the front enables the tongue F to be set at a less pitch or forward depression than the top of the bracket B, for a purpose hereinafter explained. A lip, h, depending from the front of the socket-block enables the latter to clip the front edge of the bracket. Cheeks h' h" on top of the socket-block embrace and hold the sides of the tongue, and oblige the tongue and socket block to move together as one piece. A pivot, G, confines the tongue and socket-block F H to vibrations in the plane of the bracket-top, so that when the bracket B is set with a forward pitch, as represented, the tongue-point, in swinging to one side, will sweep somewhat upward, so as to relieve the necks of the team in the act of turning.

I is a dog, which being pressed within a notch, J, in the socket-block by means of a spring, K, holds the tongue stiff. A pedal or trigger, L, connected to the dog I, enables the driver to liberate the tongue on arriving at the end of a swath, and to turn the corner with a limber tongue, so as to avoid galling the necks of the animals. The frame, being thus disengaged from rigid connection with the tongue, swings easily around the tread of the master-

wheel as a center until its momentum brings it again in line with the tongue, when the dog snaps into place again, and the implement becomes to all intents and purposes a stiff-tongued machine. The tongue, on returning to line, resumes its proper working-pitch. Apart from its great cheapness, lightness, and compactness, the arrangement proves much preferable to those whose tongue is mounted on a truck, because the cutting is resumed with more accuracy from its comparative exemption from leeway or side slip, especially on sliding ground, and also in consequence of its automatic conversion to the form of a stiff-tongued machine. The form described is that which I deem best adapted to carry out the purposes of my invention; but I do not propose to limit myself precisely thereto so long as the same results are attained by means substantially equivalent. For example, the tongue and socket-block may be formed of a single piece, the lower side of the tongue tapering rearward and being shod with an iron plate, which may be provided with the lip h. The adjustable bracket B may be replaced by a flange, permanently attached to the frame in such position as to have the desired pitch. The trigger L may be a lever of the second kind, and may be pressed down instead of being thrust forward to release the dog.

I claim herein as new and of my invention—

1. In the described combination, the pivot G, dog I, spring K, and trigger L, or devices substantially equivalent, whereby the tongue of a harvesting-machine is rendered laterally limber at the option of the operator and restored automatically to the rigid condition, substantially as set forth.

2. The provision between a laterally-limber tongue, F, and the main frame of a harvester of the wedge-formed socket-block H, and inclined or adjustable bracket B, or devices substantially equivalent.

In testimony of which invention I hereunto set my hand.

S. K. LIGHTER.
